DELIVERY MECHANISM FOR PAPER BOX
MACHINES

Edwin G. Staude, Minneapolis, Minn.

Application May 23, 1936, Serial No. 81,512

12 Claims. (Cl. 271—76)

This invention relates to improvements in delivery mechanisms, particularly to improvements in that type of delivery mechanism shown in my Patent No. 1,986,023.

5 An important object of this invention is to drive the delivery belt at its forward end only, and to obtain and maintain a pulling action on the upper stretch to keep the stretch taut at all times, and to urge it against the overlying pressure unit, 10 or interposed articles, thus automatically adjusting the space between the belt and the pressure unit conformably to the varying thicknesses of the lapped or stacked articles; particularly where feeding is irregular, and where, but for this invention, the stack would be irregular. This device insures continuous feeding in the direction of belt travel.

A further object is to provide an improved pressure unit, consisting of means, in this instance 20 linked roller sections, adapted for what may be termed "caterpillar" action, to automatically compensate for varying thicknesses of lapped articles, due to uneven feeding, and acting to maintain uniform pressure on the glue seam of a folded 25 carton or box blank, to insure firm adhesive sealing and prevent opening of the blank while it is under the pressure unit.

Other objects of my invention will appear from the following detailed description of the drawings, 30 and in said drawings

Figure 1 is a longitudinal sectional elevation of my delivery mechanism, as before delivery of blanks thereto, illustrating the manner in which the pull on the upper stretch causes the stretch to 35 bear against the drive pulley pressure section, thus delivering the slack into the lower stretch of the belt;

Figure 2 is a view similar to Figure 1, showing the cartons or box blanks irregularly fed into the 40 delivery, and illustrating the manner in which the conveyor belt is permitted to sag below the drive of the pressure unit to make room for the folded cartons or blanks, taking the surplus length of belt from the slack in the lower stretch. This 45 figure also shows the manner in which the hinged roller trucks of the pressure unit adapt themselves to the uneven surface of the upper sides of the unevenly fed cartons or box blanks;

50 Figure 3 is a side elevation, with the machine shortened by breaking away the middle of the apparatus;

Figure 4 is a detail longitudinal section showing the delivery mechanism set up for overhead 55 stacking;

Figure 5 is a view similar to Figure 4, with the mechanism adjusted for underneath stacking;

Figure 6 is a plan view of my invention with a portion of the center broken away as in Figure 3;

Figure 7 is a section on line 7—7 of Figure 3, 5 looking in the direction of the arrow;

Figure 8 is a top view of the linked roller sections of the upper pressure unit, and some of the associated parts;

Figure 9 is a plan section showing the manner 10 of linking the roller sections;

Figure 10 is a section on line 10—10 of Figure 7; and

Figure 11 is a sectional detail of the drive pulley of the pressure device, illustrating the manner 15 of adjustably mounting same on the drive shaft.

Referring to the drawings, 2 generally indicates a paper box machine, including feeding delivery belts 3 and 4 which are adjustable to deliver the folded carton, box or blank to a slower moving conveyor belt 5.

The conveyor belt 5 is driven by a drum 6 mounted on a shaft 7, to which shaft is keyed a worm wheel 8, see Figures 3 and 6, meshing with 25 a worm 9 that in turn is keyed to a shaft 10. The shaft 10 is driven from the box machine at different speeds through a selective chain mechanism 11. The particular speed is selected by the operator and depends upon the length and thickness of the article which is to be handled. Mounted on the shaft 10 is a worm 12 meshing with a worm wheel 13, mounted on a stud 14.

To the worm wheel 13 is secured a sprocket 15 having chain 16, see Figure 7, operating sprocket 35 17 which is keyed to a stub shaft 18 having spur gear 19. The stub shaft 18 operates in a bearing 20. The gear 19 in turn meshes into a spur gear 21 which is secured to a shaft 22, in turn driving a pulley 23, see Figure 11, splined to the shaft 22 as at 24. The pulley 23 is kept in position by a forked member 25, see Figures 8 and 4, which is secured to a tube 26 having a curved member 27 and a pivot at 28 in the foremost hinged truck section 29. This truck carries a 45 pulley 30 over which passes a belt 31 which also passes over pulley 23.

Attached to the inner end of truck section 29 is a second truck 32. This is a hinged attachment concentric with a roller 33 of truck 39 (see Figure 9). The hinging is accomplished by a stud 32' passing through openings 33' in the ends of the sides of the truck members 29 and 32. The ends of the side members of truck 29 and the corresponding ends of the side members of 55

the truck 32 are halved together to present an even or flush surface on the outside. In this embodiment, four roller trucks are employed to obtain a kind of caterpillar structure and action, 5 that is a flexible action. The ends of the sides of the trucks 32 and 34 are connected in the same manner as the ends of the sides of trucks 28 and 32. Each hinge roller 33, 35 and 37 is provided with a sleeve 35', which passes through 10 the offset ends of the truck sides and serves as a spacer to keep the straight ends of the side members of truck 32 apart, and with said ends pivoting on the ends of the sleeve 35'. This permits 15 tightening of the stud 32' without binding on the pulleys 33, 35 and 37.

Mounted on the roller truck 36 is a U-shaped casting 38 which straddles the tube 28 and serves as a rear guide for the linked connecting trucks to allow vertical but prevent lateral motion. 20 Mounted at the top of the member 38 is an arm 39 which is provided with an idler pulley 40 to take up the slack in the belt 31, when the trucks raise due to variation in thickness of the stack of lapped cartons, boxes or blanks. 25 To adjust the shaft 22 (which carries pulley 23) for different heights, see Figures 6 and 7, it is provided at opposite ends with levers 41 each having a rack 42 on its upper arm meshing with a pinion 43 of shaft 44. A hand wheel 45 is provided on the shaft 44 for adjusting the shaft, and a clamp screw 46 holds the shaft 44 in rigid 30 adjusted position.

The upper stretch of the belt 5 is supported by a roll 47 at the forwardmost position and a roll 35 48, and is also supported by a flat board 49 and by a flat board 50. The board 50 serves to hold the belt 5 in flat condition in the region of the upper pressure device to prevent weaving at this point and to insure accurate drying of the glue 40 seam without slipping the seam during the drying process. A pulley 51 supports the belt when the conveyor is filled with blanks, as shown in Figures 2, 4 and 5. Another pulley 52 supports the belt at the feeding end of the box machine 45 or receiving end of the delivery mechanism. This pulley 52 is adjustable in a slot 53 of arms 54 secured to a shaft 55 which in turn is mounted on a bracket 56 secured to a frame member 57. Arms 54 are adjustable in a vertical plane.

50 The pressure section, including the pulley 23 and the rollers 48 and 51, is mounted on a carriage which consists of a bracket 58 and 59 having rollers 60 to bear on the upper surface of the frame 57. A pair of longitudinally extending tie rods 61 connect the brackets 58 and 59 and provide an adjustable support 62 for the roller 51. The adjustable support for the roller 51 consists of a threaded shaft 63 adjustable in the vertical direction and held in adjusted position by spanner wrench nuts 64 and 65. The board 50 is hinged at the forward end about the shaft which supports roller 48 and its degree of inclination can be varied also by means of the shaft 63. In this case, the roll 51 is mounted on 60 the board and both roll and board are adjusted together.

A pair of brackets 66 (see Figures 7 and 10) mounted on the bracket 58, support the upper pressure section through a pin 67 and a sleeve 68 70 that furnish a pivot for the sector member 42.

A suitable belt tightener, see Figure 3, includes tightener roll 69, controlled by the tightener lever 70, having ratchet teeth 71 and a pawl 72. The purpose of this tightener is to control excessive slack in the belt 5 due to possible stretch 75

in use and also to guide the belt under the cross shaft 73 on the movable carriage which supports the bracket 58.

I claim as my invention:

1. A device of the class described including, 5 means for feeding flat articles, a delivery belt to which said means delivers articles in lapped relationship, a pressure device cooperating with the upper stretch of said belt, and a flat surface over and against which said belt travels, said 10 surface being located beneath the major portion of said pressure device.

2. A device of the class described including, 15 means for feeding flat articles, a delivery belt to which said means delivers articles in lapped relationship, a pressure device cooperating with the upper stretch of said belt, and driving means for said belt acting only at the forward end thereof to cause said stretch to remain taut as a result of pulling effort on its forward end and 20 bear against the pressure device, and a flat surface over which said belt travels and which supports said belt, a part of the flat surface being located beneath a part of the pressure device.

3. A device of the class described including, 25 means for feeding flat articles in lapped relationship, a delivery belt, a pressure device cooperative with the upper stretch of said belt, said device comprising a series of hinged roller trucks 30 adapted to individually adjust themselves to conform to varying thicknesses of overlapped articles.

4. A device of the class described including 35 means for feeding flat articles in lapped relationship, a delivery belt, a pressure device cooperative with the upper stretch of said belt, said device comprising a plurality of linearly related 40 hinged together roller trucks adapted to individually adjust themselves to different thicknesses of overlapped articles.

5. A device of the class described including 45 means for feeding flat articles, a delivery belt to which the feeding means delivers articles in lapped relationship, and a pressure device cooperating with the upper stretch of said belt or articles thereon including plural swinging means adapted for independent motion to exert uniform 50 pressure on the lapped articles conformably to different thicknesses thereof.

6. A device of the class described including, 55 means for feeding flat articles, a delivery belt to which the feeding means delivers articles in lapped relationship, a pressure device cooperating with the upper stretch of said delivery belt comprising a series of hinged roller trucks 60 adapted to conform to different thicknesses of the overlapped articles, and a flat support for said upper stretch extending under a substantial portion of said pressure device.

7. A device of the class described including, 65 means for feeding flat articles, a delivery belt to which the feeding means delivers articles in lapped relationship, a pressure device cooperating with the upper stretch of said delivery belt comprising a series of independently swingingly 70 acting elements adapted to conform to the varying thicknesses of the overlapped articles, and a flat support for part of said upper stretch which lies in opposition to said pressure device.

8. A delivery mechanism comprising a delivery 75 belt adapted to receive and support articles in overlapped relation, a pressure device arranged above the belt and having a belt having a lower stretch cooperative with the upper stretch of the delivery belt, and weighted means having 75

independently acting parts which are swingingly interconnected and which bear upon the inner side of the lower stretch of the upper belt, and adapted to cause the stretch to conform to different thicknesses of overlapped articles lying between the runs.

9. A delivery mechanism comprising a delivery belt adapted to receive and support articles in overlapped relation, a pressure device arranged above the belt and having a belt having a lower stretch cooperative with the upper stretch of the delivery belt, flexible weighted means including a series of hinged trucks bearing upon the inner side of the lower stretch of the upper belt, and adapted to cause the stretch to conform to different thicknesses of overlapped articles lying between the runs, and a flat support for and lying beneath the upper stretch of the delivery belt, and in opposition to said weighted means.
10. A device of the class described including, means for feeding flat articles, a delivery belt to which said means delivers articles in lapped relationship, a pressure device cooperating with the upper stretch of said belt and means to hold a portion of said upper stretch in flat relation

comprising a flat board and means for adjusting it to move the belt toward or away from said pressure device.

11. A device of the class described including, means for feeding flat articles, a delivery belt to which said means delivers articles in lapped relationship, a pressure device cooperating with the upper stretch of said belt and means to hold a portion of said upper stretch in flat relation to said pressure device said means comprising a flat board hinged at its forward end and having means at its rear end for vertically adjusting that end.

12. A device of the class described including, means for feeding flat articles, a delivery belt to which said means delivers articles in lapped relationship, a pressure device cooperating with the upper stretch of said belt, means in opposition to said pressure device to prevent sagging of a relatively large portion of said upper stretch which is beneath the lapped articles, and a pair of rolls so arranged as to allow a portion of said upper stretch to sag as it approaches said sag-preventing means.

EDWIN G. STAUDE. 25
